UNITED STATES PATENT OFFICE.

FRANZ MAX BERBERICH, OF KIEL, GERMANY.

DEVICE FOR MIXING AND RENDERING LIQUIDS HOMOGENEOUS.

1,112,050.

Specification of Letters Patent. Patented Sept. 29, 1914.

Application filed October 11, 1912. Serial No. 725,114.

To all whom it may concern:

Be it known that I, FRANZ MAX BERBERICH, chemist, a subject of the German Emperor, and resident of No. 8 Zastrowstrasse, Kiel, Germany, have invented certain new and useful Improvements in Devices for Mixing and Rendering Liquids Homogeneous, of which the following is a specification.

10 This invention relates to a device for the mixing and rendering homogeneous of liquids, and more particularly adapted for the treatment of milk in order to counteract the separation of cream therefrom. To 15 this end the liquids are forced through one or several adjustable passages after which they are so guided under decreasing pressure as to be caused to return and to meet the on-coming liquid in a counter-current. 20 In order to effect this use may be made of a simple cylindrical body, which is inserted in a casing so as to form with this casing an adjustable passage, all parts of the structure being stationary when in operation. 25 Around this passage a groove is arranged in the casing, in which the liquid after traversing the passage, penetrates and then returns and is discharged. In the place of one simple cylindrical body a combination of several in the form of a conical stepped body may be used in which case the pressure of the liquid gradually decreases from the apex of the cone to the base. The current of liquid is then so 30 guided that after each exit from the passage formed by one step and its seat, it enters the adjacent groove, after which it returns and is forced in the counter current to the next step, at which the same operation is 35 repeated. In this manner the liquid is rendered homogeneous to a greater degree than is the case with the known processes, in which a pressure of 150 and more atmospheres is employed as against a considerably less pressure employed according to 40 the present method. The result is a better product coupled with a considerable economy of power and a considerably reduced wear of the apparatus, so that a substantial 45 improvement is attained.

Two constructional forms of a device according to this invention are shown by way of example in the accompanying drawings in which—

50 Figure 1 illustrates a longitudinal section of one form of the device provided with a

stepped filling body. Fig. 2 is a section on the line A—B of Fig. 1 and Fig. 3 shows another form of the device provided with a cylindrical filling body.

According to Figs. 1 and 2 the device consists of a rectangularly bent tubular portion *a* provided with a passage *b* and connected to a casing *c*, the central passage *d* of which coincides with the passage *b*. The casing *c* is provided with a cavity having a stepped forward and a cylindrical rearward portion. Flush with the stepped parts or shoulders *e* of the casing *c* are formed within the casing *c*, a plurality of laterally extending grooves *f*, that open at their inner ends into the central cavity of said casing, while they are closed along their outer ends to form what may be termed a series of "blind alleys." Arranged in the cavity of the casing *c* is a normally stationary body or filling piece *g* which is likewise provided with stepped parts so arranged as to form with the casing *c* annular spaces *h*. These annular spaces *h* cannot be varied, whereas the stepped portions *i* on the body *g* and the shoulders *e* of the casing *c* are capable of being adjusted with the aid of a spindle *k*, to such an extent that only extremely narrow passages remain between them. The body *g* moreover is provided with ducts *l*. Attached to the casing *c* is a bent pipe *m* in which the screw spindle *k* is guided, and which is provided with a discharge passage *n*.

The liquid to be treated and admitted through the pipe *a* is forced through the passages *b*—*d* into the casing *c*, by way of the fine passages between the shoulders *e* and steps *i*, entering the grooves *f* in the form of a thin sheet, which by the edges in these spaces is deflected downwardly and caused to return until it reaches the annular spaces *h* whence it is forced in a fine sheet between the next following step portions of the casing and of the body *g*, into the next grooves *f*, and so on until the liquid is discharged through the ducts *l* and the passage *n*.

By the operation described, the extremely thin liquid sheet entering under pressure any one of the grooves *f* is forced to return within said groove as it can flow outwardly only until checked by the outer closed end thereof. In this way the inflowing current is caused to meet the outflowing current within the groove, whereby a frictional con-

tact between the liquid particles is obtained which effects the desired homogeneity of the liquid.

According to Fig. 3 the device is provided with a cylindrical filling piece or body o connected to or extended to form a stem o' , which is capable of being adjusted by means of a hand-wheel o^2 and fixed in its adjusted position by the hand-wheel o^3 .
10 Arranged in the casing p is a central passage r through which the liquid is introduced. The end of this passage is flared so that an annular edge p' is produced, which with the adjacent face of the filling piece o forms a passage which is adjustable by means of the stem o' . Communicating with this passage is a groove s which in turn communicates with a discharge passage t , from which the liquid is ultimately discharged 20 through the socket u .

What I claim is:—

1. A device for rendering liquids homogeneous comprising a casing having a liquid inlet, a cavity and a liquid outlet, a body arranged within said cavity to form a passage therebetween, the casing being provided with a laterally extending groove that is closed at its outer end and opens at its inner 25

end into said passage, all parts of the structure being stationary when in operation. 30

2. A device for rendering liquids homogeneous comprising a casing having a liquid inlet, a cavity and a liquid outlet, a body arranged within said cavity to form a liquid passage therebetween, means for adjusting 35 said body and thereby adjusting the liquid passage, the casing being provided with a laterally extending groove that is closed at its outer end, and opens at its inner end into said passage, all parts of the structure being 40 stationary when in operation.

3. A device for rendering liquids homogeneous comprising a casing provided with a stepped cavity, the step portions of the casing terminating in annular grooves, and a stepped adjustable body arranged within the casing with which it forms annular spaces adjacent to the grooves, all parts of the structure being stationary when in operation. 45

Signed by me at Bremen, Germany, this 26th day of September, 1912.

FRANZ MAX BERBERICH.
